UNITED STATES PATENT OFFICE.

MONTEZUMA SAIN, OF PERU, INDIANA.

RAIL-FASTENER.

1,174,615.

Specification of Letters Patent.

Patented Mar. 7, 1916.

Application filed December 4, 1915. Serial No. 65,037.

To all whom it may concern:

Be it known that I, MONTEZUMA SAIN, a citizen of the United States, residing at Peru, in the county of Miami and State of Indiana, have invented a new and useful Rail-Fastener, of which the following is a specification.

My invention relates to improved means for fastening and effectively locking rails to ties, adapted for use with either wooden, concrete or metal ties.

It is an object of my invention to provide a device of this character which is locked by one operation; in which the usual spikes and bolts are not required; and which will not work loose.

It is a further object of my invention to provide a novel combination and arrangement of parts, as more fully hereinafter set forth and claimed.

One of the principal objects of my invention is to prevent the creeping of rails.

I attain the objects of my invention by the mechanism illustrated in the accompanying drawings, in which—

Figure 1 is an end view of my rail fastener, with the rail shown in cross section; Fig. 2 is a top plan; Fig. 3 is a section through the tie on the line 3—3 of Fig. 2, the rail fastener being shown in side elevation; and Fig. 4 is a section through the fastener, on line 4—4 of Fig. 2, the tie being shown in elevation.

Like characters of reference designate like parts throughout the several views.

Referring to the accompanying drawings, the tie is designated by 1, and the rail by 2. The tie may be of wood, concrete or metal, my fastener being adapted for use with any suitable tie. I provide plate members 3 and 4, having overlapping flanges 19 and 20, respectively, as illustrated in Figs. 2 and 4. Plate 3 is provided with a rail engaging flange 17, and plate 4 with a similar rail engaging flange 18, overlapping the base flanges of rail 2, as shown in Figs. 1, 2 and 4.

Plate 3 has a downwardly extending flange 5 extending down the side of the tie and provided with lugs 7 positioned to engage in suitable recesses 9 in tie 1. Plate 4 has a downwardly extending flange 6 extending down the side of the tie opposite member 5. Flange 6 is provided with lugs

8 positioned to engage in suitable recesses 10 in tie 1, as illustrated in Fig. 3. Plate 3 is provided with a rail engaging end portion 11 having a slotted portion 12, into which the outwardly curved end or tongue 13 of plate 4 projects to lock the triangular plate members together at that side of the rail. Diagonally opposite locking members 11, 12 and 13 above described, I provide on plate 3, a suitable orificed portion 14, and on plate 4 a corresponding suitable orificed portion 15, adapted to be secured together by a suitable fastening bolt 16, as shown in Figs. 2 and 3, whereby the fastener may be readily secured to the tie and to the rail to securely lock the same to the tie.

The operation of the invention will be apparent from an examination of the accompanying drawings. The triangular plate members 3 and 4 are inserted under the base of the rail, with their respective flanges 19 and 20 overlapping under the base of the rail. Rail engaging portions 17 of plate 3 and 16 and 11 of plate 4 engage over opposite base flanges of rail 1 to lock the same in place. Plates 3 and 4 are locked together by the projection of the tongue or end 13 through the slotted portion 12 of member 4, said end being outwardly curved as illustrated to prevent disengagement. The locking engagement may be further stiffened by the insertion of a suitable steel wedge (not illustrated) in the slotted portion 12 to bear against the tongue or end 13, if the engagement otherwise is not sufficiently rigid. Such a wedge prevents any movement of the parts in any direction. At the diagonally opposite portion of the fastening device orificed portions 15 of plate 4 and 14 of plate 3 are secured together by the insertion of a suitable fastening bolt 16. Plates 3 and 4 are rigidly secured to the tie by the downwardly extending flanges 5 and 6, which have lugs 7 and 8, respectively, engaging in recesses 9 and 10, respectively, of tie 1.

Particular attention is directed to the fact that the device is adapted for use with wooden, concrete or metal ties, it being necessary merely to have the recesses in the sides of the tie to receive the lugs which lock the fastener to the tie. Attention is also directed to the fact that except for the fastening

bolt, the fastener consists of but two non-integral members.

The device operates to prevent the creeping of rails, the lock taking the place of a rail plate and rail brace.

What I claim is:

1. A rail fastener consisting of triangular plate members abutting one against the other and having overlapping portions engaging opposite base flanges of the rail, and having means for engaging in recesses at opposite sides of the tie to lock the fastener to the tie, and means disposed at diagonally opposed portions of the fastener to lock the triangular plate members in rigid engagement, substantially as described.

2. In a rail fastener, a triangular plate member extending under the base of the rail and having a flange adapted to overlap the base flange of the rail, and a downwardly extending portion adapted to extend down the side of the tie, and lugs projecting from said portion and adapted to engage in corresponding recesses in the tie.

3. In a rail fastener, triangular plate members extending under the rail, one of the members having a slotted portion and the abutting member having an outwardly curved end tongue adapted to lock in said slotted portion, adjoining orificed portions at the diagonally opposed corner of the fastening device, and a fastening bolt for lock-

ing the fastener in engagement with the rails.

4. In a rail fastener, means for engaging the base flanges of a rail, means for locking the aforesaid means in engagement with the basal flanges of a rail, said locking means being disposed at diagonally opposed corners, and downwardly extended side flanges extending down opposite sides of the tie and having lugs adapted to project into corresponding recesses in the tie, to lock the fastener rigidly to the tie.

5. A rail fastener consisting of triangular plate members having diagonally overlapping flanges, parallel rail-engaging flanged portions, diagonally disposed plate locking members, opposite downwardly extending side flanges for both of the plate members, and inwardly projecting lugs for each of said side flanges, said lugs being adapted to lock the rail fastener in engagement with recesses in the tie positioned to receive the lugs, whereby the rail may be rigidly fastened by the device to ties of wood, concrete or metal.

In testimony whereof I hereunto affix my signature in the presence of two witnesses.

MONTEZUMA SAINÉ.
